UNITED STATES PATENT OFFICE.

GILBERT McM. ROSS AND DANIEL GRANT, OF VIRGINIA CITY, NEVADA.

DIAMOND DRILL AND WELL SINKING OR BORING SAFETY-MACHINE.

SPECIFICATION forming part of Letters Patent No. 284,067, dated August 28, 1883.

Application filed May 8, 1883. (No model.)

To all whom it may concern:

Be it known that we, GILBERT McM. Ross and DANIEL GRANT, citizens of the United States, residing at Virginia City, county of Storey, and State of Nevada, have invented 5 a new and useful Diamond Drill and Well Sinking or Boring Safety-Machine; and we do hereby declare the same has not been patented to us, or either of us, or to others with our 10 knowledge and consent in any country whatsoever.

Our invention relates to an attachment to a diamond drill in mines, and to well sinking or 15 boring machines for gas, oil, or water from the surface of the earth or elsewhere, by the use of which a sudden and sometimes dangerous influx or wasteful discharge of the material sought to be discovered is controlled by the operator of said machines when found, so 20 that the same can be restrained within the limits desired, or conducted, should its force be sufficient, to any desired point, thereby insuring absolute safety from or control of the water encountered in the running of diamond 25 drills in mines and the boring for water, gas, or oil from the surface or elsewhere, and securing protection to the life of the person or persons drilling under ground, with an avoidance of the flooding of the mine, with security 30 from waste or firing of the material found in boring from the surface or elsewhere for oils and gas. Without the use of said machine it now often happens that the lives of those engaged in drilling in mines are endangered by a 35 sudden flow of water from the hole thus run, and work at least temporarily suspended by reason thereof, or a waste or firing, with loss of life and property, in the boring for coal oil or gas, as aforesaid, when the same reaches 40 the surface, all for the want of means or appliances to properly restrain or control the same, the objects of our invention being to furnish a proper appliance or machine to restrain or control such liquids so encountered. 45 We attain these objects by means of the mechanism illustrated in the accompanying drawings, similar letters referring to similar parts.

A A is a pipe inserted in a hole prepared for the drill rope or borer V V, and also represents the casing of a well. B B is a collar or flange shrunk on the pipe A A for the pur-

pose of driving the pipe A A into position, and as a point to brace from to keep pipe A A in place. C C is a peet-valve screwed onto pipe A A. D D is a nipple screwed in valve 55 C C. E E E is a T screwed onto nipple D D. F F F F is a stuffing-box screwed in T E E E. G G is a wrench on stuffing-box F F F F for tightening packing H H on diamond-drill rod, rope, or borer V V. H H is the packing in 60 stuffing-box F F F F. I I is a nipple screwed in T E E E. J J J is a reduced T screwed on nipple I I. K K is a nipple screwed on reduced T J J J. L L is a service-cock screwed on nipple K K. M M is a nipple screwed in 65 service-cock L L. N N is a wrench on service-cock L L. O O is a nipple screwed in reduced T J J J. P P P is a reduced T screwed on nipple O O. Q Q is a nipple screwed in reduced T P P P. R R is a valve or service-cock 70 screwed on nipple Q Q. S S is a wrench on valve or service-cock R R. T T is a valve or service-cock screwed in reduced T P P P. U is a pressure-gage. V V shows diamond-drill rod, rope, or borer in place. 75

When the pipe A A has been properly secured in the ground, the machine, as hereinbefore specified, is attached to pipe A A, the gate of the valve C C is then opened, and the rod, rope, or borer V V inserted through stuffing-box F F F F, T E E E, nipple D D, valve C C, and pipe A A. The packing H H in stuffing-box F F F F being loose, drilling or boring is then commenced, while service-cock L L remains open and valves or service-cocks 80 R R and T T are closed. In the event of striking the water, gas, or oil, or other liquid sought to be controlled, the drilling or boring machine, to which the parts hereinbefore specified are attached, is stopped, and the wrench 85 G G on stuffing-box F F F F is turned so as to tighten the packing H H on the diamond-drill rod, rope, or borer V V, and the wrench N N on service-cock L L is turned off, closing the service-cock L L. The water, gas, oil, or other liquid being thus and now under control, service-cock or valve T T is then opened, and the pressure of the water, gas, oil, or other liquid is ascertained by the indicator U. If further drilling or boring is desired, and the 90 pressure of water, gas, oil, or other fluid, as shown by the indicator U, is found to be 95

- great, pipes can be attached to valve or service cock R R, and thus conduct the water, gas, oil, or other fluid to any point that the pressure may admit of, or be retained at the point of encounter. Meanwhile the service-cock L L is opened at intervals sufficiently frequent to admit of the discharge of the accumulating sand or other heavy particles, which in the case of drilling by the diamond drill can be used as samples of the material passed through. When the diamond-drill rope or borer has reached the desired point, and if a pressure of water, gas, oil, or other liquid is present, wrench G G is turned, loosening the packing H H in stuffing-box F F F F sufficiently to admit of the withdrawal of the diamond-drill rod, rope, or borer V V. The rod, rope, or borer V V is then withdrawn until the bit of the diamond drill or point of the rope or borer reaches T E E E. The gate of valve C C is then closed and the diamond-drill rope or borer V V withdrawn, and all of the machine herein specified with the exception of pipe A A and collar or flange B B and valve C C is withdrawn, and pipes can then be connected with valve C C, and the water, gas, or oil may be conducted to any desired point, as hereinbefore described. Then the balance of the machine, with the addition of a new pipe A A and collar or flange B B and valve C C, can be used for further or other drilling, boring, or well-sinking operations.
- What we claim, and desire to secure by Letters Patent of the United States, is—
1. The combination, in a diamond drill and well sinking or boring safety-machine, of the stuffing-box F F F F with the packing H H and the wrench G G, for the purpose of tightening the packing H H upon the diamond-drill rope or borer V V, with the diamond-
  - 5 drill rod, rope, or borer V V placed and working within the pipe A A, to which is shrunk the collar or flange B B, substantially as set forth.
  2. The combination, in a diamond drill and well sinking or boring safety-machine, of the valve C C with the rod, rope, or borer V V, inserted through stuffing-box F F F F, T E E E, (which is provided with nipple I I,) nipple D D, valve C C, and pipe A A, to which is shrunk the collar B B, substantially as described.
  3. The combination, in a diamond drill and well sinking or boring safety-machine, of the service-cock L L with the nipple K K and reduced T J J J, and the nipple O O, screwed in reduced T J J J, and the nipple M M, in combination with the wrench N N, to which—that is, nipples K K and M M—the several discharge-pipes may be attached, with the service-cock or valve R R, provided with the wrench S S, and service-cock or valve T T, substantially as described.
  4. The combination, in a diamond drill and well sinking or boring safety-machine, of the reduced T P P P with service-cock T T and pressure-gage U, nipple Q Q, and service-cock or valve R R, provided with wrench S S, in combination with service-cock L L and wrench N N, for the purpose of regulating the flow of water, gas, oil, or other liquid and ascertaining the pressure of the same, substantially as described, all said parts being arranged and adapted to operate essentially as set forth.

GILBERT McM. ROSS,
DANIEL GRANT.
